UNITED STATES PATENT OFFICE.

ERIK AUGUST BOLINDER, OF STOCKHOLM, SWEDEN.

METHOD OF JOINTING SHELLS OF BARRELS AND CASKS OR PARTS THEREOF.

Application filed June 25, 1920. Serial No. 391,725.

To all whom it may concern:

Be it known that I, ERIK AUGUST BOLINDER, subject of the King of Sweden, residing at Jaktvarvsgrand 4, Stockholm, Sweden, have invented certain new and useful Improvements in Methods of Jointing Shells of Barrels and Casks or Parts Thereof, of which the following is a specification.

The present invention relates to a method 10 of making barrels and casks, and particularly bears on that stage of the process which consists in jointing the shell or parts thereof, or in filling the space or opening in the shell which is still to be filled up after 15 all of the staves but the last one have been brought onto each other or joined in some way or other.

The method, which is exceedingly simple and effective, is applicable to barrels and 20 casks of all kinds, cylindrical as well as bulging ones, but it is best suited for the latter type of barrel. If bulging barrels and casks are built up from tongued staves slid onto each other in the longitudinal direction, the peculiar state of things is met with 25 that the last stave in the wall of the barrel cannot be simply slid into its place, the space remaining in the shell of the barrel after the latter has been nearly completed being 30 wider at the middle than at the ends thereof.

The method aimed at by the invention is primarily characterized by this that the shell of the barrel is provided in one or more 35 places with an opening or interstice with parallel or nearly parallel edges having dove-tailed or similarly shaped tongues between which is slid a rail correspondingly shaped and tenoned so as to cause the tongued-parts thereof to engage with the grooved-parts of the barrel shell.

The method may be carried into effect in 40 various ways. For example, the said connecting rail may be made of a thickness equal to that of the wall of the barrel, that 45 is to say, it may be made and secured so that the outer and inner sides thereof will be flush with the outer and inner sides of the barrel, or the rail may be made not quite 50 as thick as the wall of the barrel and slid into the outer or inner half-part of the thickness of the wall, that is to say, so that the outside or the inside of the rail will be flush with the outside or the inside of the 55 barrel, or the rail may be slid into a dove-tailed cavity which is enclosed by the wall

or shell of the barrel in such a manner that it will not reach either the outside or the inside thereof.

The accompanying drawing illustrates 60 the method as set forth hereinabove. Fig. 1 is a side view of one of the staves of the barrel shell, the said stave being provided with an interstice or opening having continuous parallel edges with a rail inserted therebetween. Figs. 2 and 3 show in elevation and a bottom plan view respectively, a barrel built up by applying the method as set forth. Figs. 4, 5 and 6 illustrate modifications of the method.

According to Figs. 1-3, the method is applied in making a bulging barrel, the staves of which are provided with dove-tailed tongues and grooves and connected with one another by sliding the tongued and grooved parts longitudinally into each other. When the staves of such a barrel but one have been joined in the manner set forth, there remains according to Fig. 2 a space 1 between the two outermost staves, which space is 70 wider at the middle than at the ends thereof, in accordance with the shape of the last stave. Obviously, it cannot be undertaken to insert a whole stave of the ordinary shape into the space thus formed. To fill the said space, the present invention is applied as 75 follows. According to the example shown, the stave which is to fill the space in question comprises two parts which, with their edges extending after continuous curves, fit 80 into the edges of the two last staves in the barrel shell so that they may be slid into engagement therewith in a longitudinal direction. The edges of the parts 2 facing 85 each other are parallel, that is to say, according to the invention, there is between them an interstice in the shell of the barrel.

Fitting into this interstice is a rail 4, the width of which corresponds with the width of the interstice, while the edges thereof are tongued or grooved in a dove-tail fashion in correspondence with the groove or tongue at the edges of the interstice. Thus the rail may slide into the interstice without any hindrance, and this having been done the 90 shell of the barrel is completely closed.

Before sliding in the rail it is arched, preferably after a circular arc, so as to be capable of being slid in without resistance, but if the rail can be made from a flexible 95 sort of wood, it will not be necessary to arch it before it is slid in place, as the rail may,

by reason of the flexibility thereof, assume the arched shape when being slid in place.

Such rails may evidently be slid into the barrel shell in more than one place. In the embodiment shown in Fig. 3 there are thus two rails 4 inserted in diametrically opposed places. By the latter arrangement the practical advantage is attained, that it will be possible to manufacture the barrel shells in halves which, lying in each other so as to occupy a small space, may be transported to the place where they are to be used and subsequently put together by sliding in the rails 4.

In the modified method according to Fig. 4, the cross section of the rail only takes up part of the thickness of the barrel shell, as will be seen from the drawing, its outer side coinciding with the outside of the shell. According to Fig. 5 the rails are so arranged that they will not reach either the outside or the inside of the barrel shell. The latter

embodiment and other embodiments may obviously be applied so that a rail may be inserted between each stave in the barrel.

What I claim as new and desire to secure by Letters Patent of the United States is:—

A method of jointing shells of barrels having a diameter larger at its middle portion than at the ends consisting in providing parallel edges of the shell with interlocking means, forming a rail and providing the same with complementary interlocking edges then inserting the rail between said parallel edges and finally sliding the rail longitudinally of the edges to effect locking engagement of the rail to the edges of the shell.

In testimony whereof I affix my signature in presence of two witnesses.

ERIK AUGUST BOLINDER.
